SIDNEY B. SILL, OF THREE RIVERS, MICHIGAN.

Letters Patent No. 73,842, dated January 28, 1868.

IMPROVEMENT IN HEAT-RADIATORS.

The Schedule referred to in these Letters Patent and making part of the same.

TO ALL WHOM IT MAY CONCERN:

Be it known that I, SIDNEY B. SILL, of Three Rivers, in the State of Michigan, have invented certain new and useful Improvements in Heat-Radiators; and I hereby declare that the following is a true, full, and exact description of the same, reference being had to the accompanying drawings, and to the letters of reference marked thereon. In the annexed drawings, which make a part of this specification—

Figure 1 represents a central vertical section of my radiator.

Figure 2 is a plan view of the same.

Figure 3 is a plan view of the radiator when reversed.

The body of the radiator consists of drum, A, furnished at top with collar C, and at bottom with the adjustable chamber B. D represents an oval flue, extending from the top of collar C downward to a little more than half the length of drum A. The said flue D can be raised or lowered by means of the knob k, which moves in a vertical slot, f, cut in collar C. The adjustable chamber B is designed to fit tightly in the bottom of drum A, (see fig. 1.) Into the top of chamber B is adjusted the metal plate m, which, after extending sufficiently far to cover about three-fourths of the inner circumference of B, is connected with and fastened to the vertical plate n. Into plate m a circular opening is made, with a rim around it, through which the rod h is made to pass, the said rod being soldered to damper G. The damper G, when turned in a horizontal position, is designed to close the opening in plate m, and thus prevent the products of combustion from ascending through the flue D. S represents a thin metal plate, curved at its outer edge, and soldered to the upper end of plate n in a horizontal position. The object of plate S is to fill up the space between the plate n, and the inner circumference of flue D, and thus prevent any of the products of combustion from entering the flue D.

My radiator affords four modes of radiation: first, from the chamber below the valve G; then from the fixed side flue between the plate n and the circumference of drum A; thirdly, the chamber above the valve G, and between the oval flue D and drum A; and lastly, the chamber in the oval flue D.

Having thus described my invention, what I claim, and desire to secure by Letters Patent, is—

1. The adjustable chamber B, when furnished with valve G, vertical plate n, and horizontal plate S, in combination with flue D, the whole constructed and operating as set forth.

2. The four radiating-chambers, arranged in the manner and for the purpose specified.

In testimony that I claim the above, I hereby affix my signature in the presence of two witnesses.

Witnesses:

C. W. BACKHUS,
